UNITED STATES PATENT OFFICE

DAVID FIRTH, OF FLINT, MICHIGAN, ASSIGNOR TO MARVEL CARBURETER COMPANY,
OF FLINT, MICHIGAN, A CORPORATION OF ILLINOIS

THERMOSTATIC HEAT CONTROL

Application filed June 14, 1929. Serial No. 370,809.

This invention relates to carburetion systems for internal combustion engines and has special reference to the provision of a modulated heat control produced by an interconnection of the exhaust and intake manifolds.

It is an object of this invention to provide an improved heat control governing the diversion of exhaust gases through a heating jacket associated with the intake manifold, said heat control being adapted to compensate for varying operating temperature conditions. It has heretofore been proposed to vary the heating effect on the intake manifold in inverse proportion to the extent of throttle opening, supplying a maximum amount of heat to the jacket under idling conditions of operation, and greatly restricting or entirely cutting off the supply of heat as the throttle approaches its wide open position, in order to develop the maximum power from a given engine under such conditions. One method of accomplishing this variation of heat supply is to divert exhaust gases through a heating jacket and supplying a diversion valve interconnected in step with the throttle so that the diversion valve shunts the whole supply of heating fluid through the jacket when the throttle is in idling position. The present invention relates to improved and simplified means for varying the relationship between the diversion valve and the throttle to vary the primitive position of one valve relative to the other to vary the heat supply for idling and to decrease the heat supply earlier relative to the throttle opening, in order to compensate for varying temperature conditions under which the engine is operated at different seasons of the year and different climates.

It is another object of this invention to provide a compact and simplified structure, readily manufactured and assembled and trouble-proof in service.

Other and further important objects of this invention will be apparent from the disclosures in the specification and the accompanying drawings.

50 This invention (in a preferred form) is

illustrated in the drawings and hereinafter more fully described.

On the drawings:

Figure 1 is a side elevation of an engine manifolding system with parts broken away to show features of this invention.

Figure 2 is a section on the line II-II of Figure 1.

Figures 3, 4 and 5, respectively, represent the cold, warm and hot adjusted positions of the valve of this invention when the valve is in idling position.

As shown on the drawings:

An exhaust manifold 10 is shown as having four exhaust collecting branch flanges 11 with an enlarged chamber 12 forming upper and lower segmental portions 13 of a cylinder disposed crosswise of the manifold. As shown, this chamber is midway of the length of the manifold in which case half of the exhaust gases from the engine will pass therethrough; although it will be evident that for the purposes of this invention the chamber might be located as to control a larger or smaller proportion of the exhaust gases by shifting its position towards or away from the exhaust outlet 14.

An intake manifold 15 fed by a central riser 16 is positioned beneath the exhaust manifold and a carbureter 17 is applied to the lower end of the riser 16. As shown in the drawings, a throttle valve 18 in a shaft 19, is mounted on the riser instead of in the carbureter because of certain advantages of such an arrangement, although it is to be understood that the present invention is not limited to such an arrangement.

The riser 16 is provided with an outer casing 20 defining an annular jacket space divided by diametrically opposite partitions 21 into a U-type of jacket, the two semi-cylindrical jacket spaces 22 and 23 being united beneath the lower edge of the partitions, which do not extend the full length of the jacket. A jacket 24 and partitions 25, associated with the T portion of the intake manifold, form upward continuations 26 and 27 of the spaces 22 and 23, and ports 28 and 29 in the bottom of the exhaust manifold chamber 12, on either side

of the lower cylindrical segment 13, communicate with the jacket spaces 26 and 27.

An exhaust control valve 30 is secured on a shaft 31 axially mounted relative to the cylindrical segments 13 in the chamber 12.

- 5 The front opening of the chamber 12 in Figure 1 is closed by a cover 32. A lever 34 associated with the shaft 31 is linked by a rod 35 to an extra arm 36 on a throttle control lever on the throttle shaft 19. This 10 arrangement causes the exhaust control valve to be operated in unison with the throttle valve, the exhaust control valve diverting all the exhaust gases through the heating jacket when the throttle is closed; 15 the valve opening in step with the throttle opening movement.

In order to modify the proportioning of the exhaust gas flow to the throttle opening, or more specifically to vary the primitive opening position of the exhaust control valve relative to the throttle opening, I provide two segments 37 of a cylinder enveloping the exhaust control valve, these segments being formed as a sheet metal 20 stamping with outstanding flanges 38, which cooperate with the segments 13 forming valve seats in the chamber, while the cylindrical segments 37 cooperate with the tips 25 of the exhaust control valve 30. These segments 37 are carried by a sleeve 33 surrounding the shaft passing through the cover, a lever 39 secured thereon being linked by a rod 40 to a lever 41 pivoted at 30 42 and connected at 43 to a link 44 operated by a thermostatically responsive device 45. As shown, this device comprises an expansible corrugated cylinder containing a volatile liquid, the cylinder being mounted 35 in a chamber 46 in the engine cooling radiator 47.

The operation:

The exhaust control valve 30 is shown in the position corresponding to an idling position of the throttle, both rotating counter-clockwise as the throttle opens. In Figure 1 and Figure 3 the heat modifying segments 37 are shown for the cold weather position wherein the thermostatic device is collapsed in the position shown in Figure 1. A rise 45 in the temperature of the thermostatic device causes expansion thereof which imposes a pull on the rod 40 which rotates the segments 37 clockwise through the position shown in Figure 4 to that shown in Figure 5, the latter corresponding to extreme operating temperature where a full diversion of exhaust gases is not required even for idling operation. The width and position of the 50 chamber segments 13 is chosen to correspond with the full range of movement of the heat modulating segment flanges 38, while the width of the segments 37 is so chosen as to determine the temperature at which full diversion of the exhaust gases begins to be 55

reduced by the actual opening of the valve 30 relative to the edge of segments 37 as indicated in Figure 4. Expressed in another way, the width of the segments 37 determines how far the throttle valve opens for 70 cold conditions before the division of exhaust gases through the heating jacket is reduced by a partial opening of the exhaust control valve 30.

It will thus be seen that I have invented 75 an improved and simplified heat control for varying the heat supplied to the intake manifold both in accordance with the throttle opening and the operating temperatures.

I am aware that many changes may be 80 made, and numerous details of construction may be varied through a wide range without departing from the principles of this invention, and I therefore do not purpose 85 limiting the patent granted hereon, otherwise than necessitated by the prior art.

I claim as my invention:

1. A manifolding system for internal combustion engines, including an exhaust manifold, an intake manifold and a throttle 90 valve for said intake manifold, a control valve in said exhaust manifold, a heating jacket surrounding a portion of the intake manifold and having supply and return ducts opening into said exhaust manifold on 95 opposite sides of said control valve therein, linkage connecting said throttle valve and said control valve whereby said valves operate in unison, and means cooperating with said exhaust control valve for varying the 100 primitive opening position thereof relative to the throttle valve.

2. A manifolding system for internal combustion engines, including an exhaust manifold, an intake manifold and a throttle 105 valve for said intake manifold, a control valve in said exhaust manifold, a heating jacket surrounding a portion of the intake manifold and having supply and return ducts opening into said exhaust manifold on 110 opposite sides of said control valve therein, linkage connecting said throttle valve and said control valve whereby said valves operate in unison, and a heat modulating valve 115 cooperating with said exhaust control valve to vary the effective opening position thereof relative to the throttle valve.

3. A manifolding system for internal combustion engines, including an exhaust manifold, an intake manifold and a throttle 120 valve for said intake manifold, a control valve in said exhaust manifold, a heating jacket surrounding a portion of the intake manifold and having supply and return ducts opening into said exhaust manifold on 125 opposite sides of said control valve therein, linkage connecting said throttle valve and said control valve whereby said valves operate in unison, a heat modulating valve cooperating with said exhaust control valve to 130

- vary the effective opening position thereof relative to the throttle valve, and thermostatic means for operating said modulating valve.

5. In combination with the exhaust and intake manifolds of an internal combustion engine, an exhaust control valve in said exhaust manifold, a heating jacket associated with said intake manifold and having supply and return connections opening into said exhaust manifolds on opposite sides of said control valve, means for operating said exhaust control valve to divert varying proportions of exhaust gases through said heating jacket, and means cooperating with said exhaust control valve for varying the effective initial opening position thereof.

5. In combination with the exhaust and intake manifolds of an internal combustion engine, an exhaust control valve in said exhaust manifold, a heating jacket associated with said intake manifold and having supply and return connections opening into said exhaust manifolds on opposite sides of said control valve, means for operating said exhaust control valve to divert varying proportions of exhaust gases through said heating jacket, and means cooperating with said exhaust control valve for varying the effective initial opening position thereof, and thermostatic means for operating said last mentioned means.

6. In combination with the exhaust and intake manifolds of an internal combustion engine, an exhaust control valve in said exhaust manifold, a heating jacket associated with said intake manifold and having supply and return connections opening into said exhaust manifolds on opposite sides of said control valve, means for operating said exhaust control valve to divert varying proportions of exhaust gases through said heating jacket, and a heat modulating valve cooperating with said exhaust control valve to vary the effective opening position thereof relative to the throttle valve.

7. In combination with the exhaust and intake manifolds of an internal combustion engine, an exhaust control valve in said exhaust manifold, a heating jacket associated with said intake manifold and having supply and return connections opening into said exhaust manifolds on opposite sides of said control valve, means for operating said exhaust control valve to divert varying proportions of exhaust gases through said heating jacket, a heat modulating valve cooperating with said exhaust control valve to vary the effective opening position thereof relative to the throttle valve, and thermostatic means for operating said modulating valve.

8. In combination with the exhaust manifold and carburetion system of an internal combustion engine, a heating jacket for said

carburetion system having supply and return connections to said exhaust manifold, a control valve in said exhaust manifold for diverting varying amounts of exhaust gases through said heating jacket, means for operating said exhaust control valve to divert varying proportions of exhaust gases through said heating jacket, and means cooperating with said exhaust control valve for varying the effective initial opening position thereof.

9. In combination with the exhaust manifold and carburetion system of an internal combustion engine, a heating jacket for said carburetion system having supply and return connections to said exhaust manifold, a control valve in said exhaust manifold for diverting varying amounts of exhaust gases through said heating jacket, means for operating said exhaust control valve to divert varying proportions of exhaust gases through said heating jacket, means cooperating with said exhaust control valve for varying the effective initial opening position thereof, and thermostatic means for operating said last mentioned means.

10. In combination with the exhaust manifold and carburetion system of an internal combustion engine, a heating jacket for said carburetion system having supply and return connections to said exhaust manifold, a control valve in said exhaust manifold for diverting varying amounts of exhaust gases through said heating jacket, means for operating said exhaust control valve to divert varying proportions of exhaust gases through said heating jacket, and a heat modulating valve cooperating with said exhaust control valve to vary the effective opening position thereof relative to the throttle valve.

11. In combination with the exhaust manifold and carburetion system of an internal combustion engine, a heating jacket for said carburetion system having supply and return connections to said exhaust manifold, a control valve in said exhaust manifold for diverting varying amounts of exhaust gases through said heating jacket, means for operating said exhaust control valve to divert varying proportions of exhaust gases through said heating jacket, a heat modulating valve cooperating with said exhaust control valve to vary the effective opening position thereof relative to the throttle valve, and thermostatic means for operating said modulating valve.

In testimony whereof I have hereunto subscribed my name at Flint, Genesee County, Michigan.

DAVID FIRTH.
